ROCK DRILL BIT

Malcolm H. Hubback, Seattle, Wash., assignor, by
mesne assignments, to Clarice E. Hubback

Application July 15, 1946, Serial No. 683,639

2 Claims. (Cl. 255—64)

1

This invention relates to the art of detachable rock drill bits, and namely drill bits comprised of a comparatively short cylindrical section of metal formed upon one end with a cutting edge or edges and upon the other end presenting an internally threaded sleeve which allows the bit to be screwed upon the lower end of the drill rod.

Detachable rock drill bits, as originally known, were products of the forging art, but these forged bits did not permit reconditioning upon becoming dull, and the consequence has been that the forged bit has in recent years been largely displaced by a machined bit, the principal advantage professed for the latter being an ability to resharpen the bits as the cutting edges wear down. However, each said resharpening operation removes an appreciable part of the bit's metal body, and the bits can therefore be resharpened only a limited number of times before becoming useless.

It is my object to devise a detachable rock drill bit peculiarized in that the same may be produced as a forged product, and which may be thereafter forge-reconditioned.

The drill bit of the present invention, and the structure employed in reconditioning the same, are shown in the accompanying drawings, wherein:

Figure 1 is a view in elevation taken on broken line 1—1 of Fig. 2 to illustrate a detachable rock drill bit produced in accordance with the present invention and here shown in the course of being reconditioned. The drill bit is broken away and shown partly in section.

Fig. 2 is a view partly in elevation and partly in longitudinal section, with the section taken on line 2—2 of Fig. 1.

Fig. 3 is a transverse section on line 3—3 of Fig. 2.

Fig. 4 is a perspective view of the improved drill bit.

Fig. 5 is a view of the drill bit taken partly in elevation and partly in section on line 5—5 of Fig. 6.

Fig. 6 is a front elevational view of the drill bit, and

Fig. 7 is a rear elevational view of the drill bit.

The finished bit of the present invention is illustrated in Figs. 4 through 7 inclusive, and is a product of the forging art comprising a cutting head denoted by the numeral 10 and a stock-engaging internally threaded sleeve 11. The sleeve is characterized in that the internal threads are interrupted at two or more points within the cir-

2

cumference. The interruption occurs, by preference, at diametrically opposite sides, and there are accordingly provided two threaded sectors denoted 12 and 13. The object in interrupting the threads is to admit of the employment of an expansion-type thread-forming tool, both in the course of originally forging the bit from a steel billet and when later reconditioning the bit by forging. In addition to its said interrupted thread, the sleeve is further characterized in that the depth of the threaded socket formed therein exactly corresponds with a reduced threaded stud formed upon the outer end of the drill rod to which the bit is to be applied. Thus, when the bit is screwed onto the stud end of the drill rod, there is developed not only a firm bearing engagement as between the exposed face of the sleeve and the shoulder which lies at the base of the threaded stud, but also a bottoming action of the tip of the drill rod and the floor of the socket.

Now, to enlarge upon the purpose underlying the interruption of the threads, it is quite evident that a forged detachable bit which relies for its detachability upon threads cut into a mounting sleeve must, in order that such threads be formed in the forging operation, be produced by the use of a core. If this core is made solid, the contraction of the metal upon the core in consequence of changing temperature and the metal-compressing action of the core in course of forming practically preclude removal of the sleeve by reason of the latter "freezing" onto the core. In overcoming the problem, I reasoned that an interrupted thread works equally as efficiently as a continuous thread in so far as producing a separable connection is concerned, and an interrupted thread has this advantage, it permits the utilization of a retractile thread-forming tool, and given an ability to contract the tool for removal purposes, the difficulty previously experienced in withdrawing the thread-forming core from a forged bit would be overcome.

The head of the sleeve 11 is shown provided with two sets of diametrically opposed wings 39 which project laterally beyond the perimeter of the sleeve. The head end of each wing presents a pair of diverging cutting faces 47 which slope rearwardly from a radial cutting edge 16 the outer end of which defines the outermost tip 40 of the wing. The outer edges 41 of each pair of cutting faces slope inwardly toward the longitudinal axis of the drill as they diverge from the wing tip, which is to say, the plane defined by each pair of said outer edges forms an acute angle with the respective cutting edge 16. The

outer wing surface is comprised of a pair of salient faces 17 and 18 having their line of junction 45, which I designate as a scouring edge, commencing at the wing tip 40. These faces slope slightly inwardly and are preferably planar as shown.

When the faces 17 and 18 are planar they are trapezoidal with the shorter parallel edge 42 forming part of the top edges of the quadrilateral side wall 43 of the wing. At the rearmost edges 44 of these faces the pitch of the slope of the outer wing surface is increased so that the said surface merges with the sleeve before reaching the tail end thereof. The pitch of this steeper slope is not important whereas the angular relationship between the plane of each pair of outer edges 41, and each scouring edge 45, with respect to the cutting edges 16 is vital to the longer cutting life which I achieve. Prior to my invention the scouring edge would have sloped inwardly toward the longitudinal axis of the bit an amount sufficient to intersect imaginary circles normal to and centered along the longitudinal axis of the bit and passing through the outer edges of the cutting faces. I have increased the angle between the scouring edge and the plane common to the respective pair of intersecting outer edges 41 so that my scouring edges lie laterally beyond the said imaginary circles. In other words, my scouring edges are the total locus of all points on the outer surface of the wings between the respective pairs of outer edges most laterally removed from the longitudinal axis of the drill. I prefer to effect such results by increasing the acute angle between the scouring edge and the respective cutting edge, which said increase strengthens the outer tips of the wings. But even more important is the fact that the cutting edges 16 can be re-sharpened and re-conditioned by a re-forging operation, to be later described, instead of by a machining operation as has been conventional, and such reconditioning by re-forging can be performed a greater number of times than has been heretofore possible, without materially increasing the dihedral angle between each pair of cutting faces. When my bit is sharpened the outer edge of the cutting face is moved rearwardly to a position substantially parallel to its original position such being permitted because the scouring edge extends rearwardly beyond the original outer edges 41 as before noted. In other words the edge portion 42 of the side walls of the wings is gradually diminished as the bit is sharpened. In the prior art drills the respective side walls are triangular in shape instead of trapezoidal and the rearmost ends of the outer edges of their cutting faces each stay in a virtually constant position as the drill is sharpened, thus accounting for the fact that the dihedral angle between the cutting faces necessarily increases as the drill is sharpened which reduces the cutting efficiency thereof.

The head 10 has a center bore 48 therethrough connected to the socket 14 in the sleeve. Between the wings the diameter of the bit is the same as the diameter of the sleeve to thereby form channels between the side walls of the wings through which dust and fragments resulting from the cutting operation can be ejected by the compressed air or water delivered to the cutting faces through the bore 48.

The process of forging my bit can be explained as follows:

A die body is employed which is composed of a stationary member and a movable member ar-

ranged to be clamped thereto, and formed by these members in their mating faces are recesses producing, by registration, a cavity corresponding to the surface contour of the bit which is to be produced. An axially placed bore of small diameter connects from one end of the assembled die with the head end of the cavity, and a bore having a diameter coinciding with that of the back end of the cavity leads to the cavity from the other end of the assembled die. The hot billet or slug which is to be forged is fed through the large bore into this cavity, and an upsetting ram is driven hard against the billet from the back end of the latter. The upsetting ram has a piston-head and a shoulder lying to the rear of the head, and the head, in point of its shape, roughly approximates the threaded socket which is to be produced in the sleeve of the finished bit. This shape, more especially, is such as presents cut-away portions at diametrically opposite sides and with these reentrant openings, as with the diametrically opposed horns which lie therebetween, having their perimeters made arcuate and concentric with the axis of the piston-head. It will be understood that the walls of this piston-head are plane-faced, the forming of the interrupted threads being the office of a thread-forming tool employed in a later step of the forging operation. The piston-head and its following shoulder act together to squeeze the billet into the crevices of the cavity, and work in conjunction with a piercing punch which is driven inwardly through the small bore, and there is produced from this initial ramming step of my forging operation a forged product substantially similar to that illustrated in Figs. 4 through 7 of the drawings excepting that the lands which lie at diametrically opposite sides of the bit's rear-end socket are as yet lacking the threads of the finished product. The next step is to transfer the partially finished bit to a second clamping die having a cavity corresponding in point of its side wall structure to the shape of the bit, and within this latter die holding the forged bit against a backing block while producing the interrupted threads. Used for this purpose is a tool having retractile thread-forming jaws, and this tool is quite similar in point of construction to the thread-reconditioning tool illustrated in Figs. 1 and 2, hence need not be separately illustrated. There is now produced a detachable rock drill bit in forged form having the shape of the bit illustrated in the drawings.

For forge-reconditioning my bit, there is employed a structure composed, as with the original forging dies, of a top and a bottom die member, and these die members act in conjunction to produce a receiving cavity for the bit quite similar to the receiving cavity of the second of the two forming dies heretofore described. This is to say that the die cavity substantially corresponds in point of its side wall structure to the external wall of the bit, and has its longitudinal wall-grooves, and namely those grooves into which the V-edges of the wings fit, prolonged forwardly a material distance beyond the die cavity proper. These prolongations of the wall grooves form a mounting to accommodate the slide movement of an upsetting and forming dolly which is arranged and adapted to be driven against a bit occupying the cavity, the driving means being comprised, preferably, of a pneumatic hammer. At the other end of the cavity, the die members accommodate the application

of a thread-reconditioning tool held against end movement. Considering the similarity between the equipment which I use for forging my detachable rock drill bit and the equipment which I employ for reconditioning the bit, it is believed that an illustration of one set of such equipment, whether it be for forging or for forge-reconditioning, should suffice for both. I have elected to illustrate my forge-reconditioning equipment, and referring to Figs. 1, 2 and 3, the top and bottom clamping dies are indicated by the numerals 20 and 21, respectively. Denoted 22 is the forming dolly having a shank 23 arranged to fit a pneumatic hammer (not shown). The thread-reconditioning tool is made sectional and is comprised of a pair of arms 24—25 having opposingly mounted jaw or nose extremities 26—27, and formed upon the perimeter of these jaws are correlated threads produced as male counterparts of the interrupted left-hand internal threads of the drill bit. To the rear of the threads, each jaw or nose is formed with a respective semi-circular thrust collar 28 arranged to lodge in a mating recess of the die.

The arms are each hinged as at 29 to a body part 30, and there is received between the arms an expander pin 31. Functional to this pin is a manually operated lever 32 forked upon its front end to straddle the pin, and providing a cam action as between the furcate branches 33 and a shoulder formed upon the pin. A split ring 34 fits over the arms and performs a spring office to yieldingly resist the expansive force of the expander pin. Other than for the employment of a power hammer to drive the expander pin, there is little difference between the expandable thread-reconditioning tool which I have illustrated and the expandable thread-forming tool used in the original forging of the bit, and which is to say the tool originally applied to produce the threads after having first created, by the use of an upsetting ram, a socket having lands therein at diametrically opposite sides.

It is believed that the invention will be clear from the foregoing. The heat employed in bringing to forging temperature the billet or the bit, as the case may be and according as the method concerned is an original forging operation or a forge-reconditioning procedure, is or may follow standard forging practice.

Having illustrated and described my invention and having explained the principles thereof, it will be understood, nevertheless, that within the scope of the appended claims, the invention may be practised otherwise than specifically illustrated and described. Furthermore, the phraseology or terminology employed herein is for pur-

poses of description and not of limitation; for it is not intended to limit the invention beyond the requirements of the prior art.

What I claim is:

- 5 1. A drill bit comprising a shank having spaced wings projecting laterally therefrom, each wing being provided at its head end with a respective pair of rearwardly sloping cutting faces which merge to form a radial cutting edge whose outer end is the outermost tip of the respective wing, the outer surface of each wing presenting a pair of salient merging faces of trapezoidal outline each having the line of juncture between said salient faces as one of its parallel edges and the edge of the adjacent cutting face as another edge thereof with the latter said edge lying radially inward of the said line of juncture, the line of juncture of each wing defining a scouring edge commencing at the respective wing tip and extending rearwardly and sloping inwardly toward the longitudinal axis of the bit to a point of termination rearward of the outside edges of the respective pair of cutting faces and forward of the tail end of the wing.
- 10 2. A drill bit comprising a shank having spaced wings projecting laterally therefrom, each wing being provided at its head end with a respective pair of rearwardly sloping cutting faces which merge to form a radial cutting edge whose outer end is the outermost tip of the respective wing, the outer surface of each wing between the outer ends of the respective pair of cutting faces comprising a respective pair of merging salient faces, the line of juncture between the salient faces defining a scouring edge, said edge sloping rearwardly and inwardly toward the longitudinal axis of the bit and lying radially outward of any circle which can be drawn through all of the said outer ends of the cutting faces.
